ASH TRAY

Floyd S. Beach, Springfield, Oreg.

Application February 17, 1953, Serial No. 23,668

Term of patent 7 years

(Cl. D85—2)

To all whom it may concern:

Be it known that I, Floyd S. Beach, a citizen of the United States, residing at Springfield, in the county of Lane and State of Oregon, have invented a new, original, and ornamental Design for an Ash Tray, of which the following is a specification, reference being had to the accompanying drawing, forming part thereof.

I claim:

The ornamental design for an ash tray, as shown.

FLOYD S. BEACH.
